UNITED STATES PATENT OFFICE.

BENJAMIN C. VANDUZEN, OF CINCINNATI, OHIO.

STEAM-PUMP.

SPECIFICATION forming part of Letters Patent No. 288,384, dated November 13, 1883.

Application filed March 3, 1883. (No model.)

To all whom it may concern:

Be it known that I, BENJAMIN C. VANDUZEN, of Cincinnati, in the county of Hamilton and State of Ohio, have invented certain new and useful Improvements in Steam-Pumps, of which the following is a specification.

My invention relates to that class of pumps in which the pressure of steam is employed to force the water or other liquid out of the pump, and in which a vacuum caused by the condensation of the dead steam may, when desired, be employed to draw the water or other liquid into the pump.

My invention is applicable to all the purposes of a steam-pump, but is also equally applicable for use as a boiler-feeder for keeping steam-boilers supplied with water.

My invention, in general, consists of one or more pump-chambers of any suitable shape, communicating on the one hand with a steam-valve and on the other hand with passages suitably controlled by valves, for allowing the liquid to enter this chamber or chambers and pass out therefrom, this chamber or chambers communicating with a cylinder containing a piston, and suitable mechanism being applied between the steam-valve and said cylinder and piston, and in connection therewith, whereby the pressure of fluid in the cylinder will operate the steam-valve, and whereby, in the manner hereinafter more particularly described, the fluid in the cylinder, which is received in one end of the latter from a pump-chamber, is discharged back into the same chamber from which it first came, either by the passage through which it first entered the cylinder from the chamber, or by another passage, or through both of passages at once. The object of a said second passage is, when present, to convey liquid into the upper portion of the chamber to condense the steam in the latter, and thus cause a vacuum to enable the pump to lift its fluid.

Another feature of my invention is a screen of novel formation for preventing the steam which is to enter the pump-chambers from passing too rapidly down onto the water or other liquid in said chamber, and thereby causing such an agitation of the said liquid as would condense the steam and prevent the said steam from acting upon the liquid till the

latter is all heated, and this screen, being heated by the said steam passing through it after the liquid has been ejected therefrom, not only enables the steam entering the chamber to act 55 immediately upon the liquid therein, but also heats the surface of said liquid as it rises through the screen to the steam-valve, (after the steam has been condensed in or has escaped from the upper part of said chamber,) 60 and this contact of said liquid with said heated screen causes that part of the liquid which subsequently meets the incoming steam when the valve is opened to be hot, and consequently said liquid will not condense said steam, 65 but will permit the latter (without the delay consequent upon condensation of the first portion of said incoming steam) to act directly and with immediate effect upon said liquid and force the latter out of said chamber. 70

Another feature of my invention consists in the combination of said screen with a novel formation of that portion of the chamber or passage communicating therewith in which the screen may be placed, whereby the space 75 between the inner side of the said chamber or passage and the screen shall be thin, for the purpose of more fully effecting the advantages set forth in connection with the preceding feature of my invention. 80

Another feature of my invention consists in means for positively moving the steam-valve by the direct pressure of the fluid in the pump-chamber, and holding the valve in place until again moved positively through the agency of 85 the cylinder and its piston, no matter what the varying pressure of steam may be upon the valve or in the chamber.

Another feature of my invention consists in means for compelling a portion of the fluid 90 discharged from the chamber to begin to operate the steam-valve when the device for operating the valve, and which is operated by the fluid from the chamber, has nearly completed its movement, and shall then, by the remainder of its movement, cause the valve to be instantly operated, for the purpose of enabling the movements of the said pump to be the better controlled. 95

Another feature of my invention consists of 100 a preferred form of device for enabling the valve to pass its center without fail.

Another feature of my invention consists of a novel means for regulating the amount of fluid received into and discharged from the piston-cylinder, and thereby regulating the 5 rapidity of the movement of the pump.

Another feature of my invention consists in forming the openings from the valve-chest into the passages communicating with the chambers in such a manner that when one of the said 10 openings is open and the steam begins to flow through the same it will strike only a small or thin edge of water standing in said opening and instantly heat the same, and hence not be condensed, and will therefore act immediately 15 in driving back the fluid through the passage communicating with said opening.

Other features of my invention and the several advantages resulting from the use of one or more of them will be fully apparent from 20 the following description:

While the various devices essential to my invention may be variously located in relation to one another, the preferable arrangement of these portions will now be shown and described 25 as follows:

Referring to the drawings forming part of this specification. Figure 1, Sheet 1, is an elevation, partly in section, of my invention, the section being taken on a vertical plane indicated by the line $x-x$ on Fig. 2. Fig. 2 is a 30 vertical sectional elevation, the section being taken at the line $y-y$ of Fig. 1. Fig. 3 is a detailed view of a portion of the valve-operating mechanism. Fig. 4, Sheet 2, is a sectional plan view of the parts below a plane indicated by the arrows $x-x$ of Fig. 1. Fig. 5 is an enlarged horizontal sectional view, the section being taken at a plane indicated by the arrows 35 $y-y$ of Fig. 2. Fig. 6 is an enlarged sectional elevation, the section being taken at the line $z-z$ of Fig. 2.

The valves for controlling the ingress of liquid into the chambers and the egress of liquid therefrom are located in a valve-box, as A^2 . 45 This box A^2 is divided by a longitudinal partition, a , into two side chambers, $a' a^2$, with which chambers the chambers $A A'$ respectively communicate through openings a^3 . (See Fig. 2.) At one end of the chambers $a' a^2$ is a transverse 50 chamber, B , extending continuously from side to side beneath the two receiving-valves $b' b^2$, and being separated from the chambers $a' a^2$ by the angular partition or box b . The inlet or supply pipe C communicates with this transverse chamber B . At each end of this transverse chamber B are the openings $B' B^2$, communicating, respectively, with the longitudinal chambers $a' a^2$, and these openings are controlled 55 by the valves $b' b^2$, which are so constructed and arranged as to permit the water entering the chamber B through the supply-pipe C to pass into the chambers a' or a^2 , but prevent any return of the water from said last-named chambers into the chamber B .

60 The preferred form of valve and support for the same is that shown in the drawings, and is as follows: In the openings $B' B^2$ are placed the

70 rings $D D'$, which rings are secured in said openings either by being screwed or driven tightly therein, and to the lower edges of these rings are connected the yokes or webs $d d'$. In the top of the box A^2 , at points directly over the openings $B' B^2$, are formed the openings $d^2 d^3$, which openings are of sufficient diameter to permit the rings $D D'$ to be passed through them to be inserted into the openings $B' B^2$. In these openings $d^2 d^3$ are secured the caps $D^2 D^3$, in the lower faces of which caps are formed the guides $d^4 d^5$, to hold in place and guide the top of the valve. 80

The valves $b' b^2$ are connected, respectively, to the valve-stems $b^3 b^4$, the lower ends of which stems pass, respectively, through the webs $d d'$ of the rings $D D'$, and the upper ends of said stems rest in the guides $d^4 d^5$ of the caps $D^2 D^3$. The upper edges of the wings $D D'$ form the valve-seats for the valves $b' b^2$. The valve-stems $b^3 b^4$ are capable of moving up and down in the webs $d d'$ and guides $d^4 d^5$, and the openings $B' B^2$ may thus be open or 90 closed.

In that portion of the box A^2 which is opposite to the chamber B is a transverse chamber, E , (see Fig. 2,) extending continuously from side to side of the box A^2 , which chamber is separated from the chambers $a' a^2$ by the angular partition or box e . This chamber E is similar to the chamber B , located at the opposite end of the box A^2 , excepting that the latter is located at the bottom of the box, the chamber E being at the top; and the function of the chamber B is to admit water into the chambers $a' a^2$, and the function of chamber E is to receive the water from said chambers $a' a^2$ and to discharge it through the outlet-pipe C . The chamber E communicates with the chamber $a' a^2$, through openings $E' E^2$, which openings are controlled by valves $e' e^2$, 95 which valves are so constructed and arranged as to permit the water to pass from the chambers $a' a^2$ into the chamber E and prevent any return of the water from said chamber E back into the chambers $a' a^2$. 100

The construction and arrangement of the valves $e' e^2$ and their connections and supports are in all respects preferably similar to the valves $b' b^2$ and their connections and supports, and it is therefore unnecessary to enter into a minute description of these valves $e' e^2$. 105

The chambers $A A'$ are preferably constructed in a cylindrical form, as shown, and upright, and these chambers $A A'$ preferably rest upon the box A^2 , the lower ends of said cylinders being provided with the flange-lugs A^4 , by which the chambers are secured to the top of the box A^2 , a suitable packing being interposed between said chambers and the box A^2 . These chambers $A A'$ may be formed together, as shown; or, if preferred, they may be separate and independent of each other. 110 The upper ends of these chambers $A A'$ are preferably conical in form, and are connected to the valve-chest (see Figs. 1, 2, and 6) by branches $F' F^2$, the valve-chest branches and 115

the flanges $f f'$, forming the upper ends of the chambers, being preferably all formed in one piece. The branches $F' F''$ are provided with the passages $f^2 f^3$, which communicate with the interior of the valve-chest F , and extend through the flanges $f f'$, and open into the upper ends of the chambers $A A'$, as shown in Fig. 6. This valve-chest F is provided with a steam-inlet pipe, F^3 , and an exhaust-pipe, F^4 .

10 Within the valve-chest F is located an oscillating valve, G . This valve G consists (see Figs. 5 and 6) of the two end flanges or disks, g , circular in form, and of a diameter equal to the diameter of the valve-chest F , which flanges 15 are connected by the box g' , which is open at the top, as shown in Fig. 6. This box g' is smaller than the diameter of the flanges g , and does not therefore come in contact with the interior of the valve-chest F , except at the 20 lower corners, at which points the box is extended by wings g^2 , which wings are at all times in contact with the interior of the valve-chest F , and below these wings g^2 is therefore formed an exhaust-chamber, G' , which has no 25 communication with the space above the wings g^2 . The distance between the longitudinal centers of these wings g^2 is exactly equal to the distance between the centers of the openings g^3 of the passages $f^2 f^3$ of the branches $F' F''$, so that when the valve G is so turned as 30 to uncover one of the openings g^3 the other will also be opened, and that when one of the openings g^3 communicates with the exhaust-space G' the other opening g^3 will communicate 35 with the space above the wings g^2 , for which reason, when steam is introduced into the valve-chest F , the instant that the valve is turned so that the steam begins to enter one of the openings g^3 exhaust-steam will begin to escape from 40 the other opening g^3 into the exhaust-space G' , from whence it will escape through the exhaust-pipe F^4 , so that while steam is passing through the passage f^2 to the chamber A the exhaust-steam from the chamber A' is passing out of 45 said chamber through the passage f^3 , and vice versa. After the valve G has been placed in position in the valve-chest F , the latter is closed by any suitable means—as, for example, by a cap, G^2 , (see Fig. 5,) which latter is secured to the valve-chest by a suitable fastening—as, for example, bolts G^3 , passing through said cap and being screwed into lugs G^4 , cast on the sides of the valve-chest. Suitable packing being placed between said 55 cap and the valve-chest, no steam can escape between the cap and the valve-chest. The side or end of the valve-chest F which is opposite to the cap G^2 is provided with an extension or neck, G^5 , through which side and extension 60 of the valve-chest passes the valve-stem H , which latter is provided with a square head, h , which fits in the box g' of the valve G , so that when the valve-stem H is turned the valve G will also be turned.

65 If desired, the valve-stem H may be formed in one piece with the valve, in which event the box g' would be in the form of a solid

block. The valve-stem H , excepting the head h , is cylindrical.

The means which I employ for rotating the valve-stem H , and through it the valve G , are as follows: Around the extension G' of the valve-chest F fits the hub h' of the crank-cam H' , which latter has an extension or arm, H^2 , and secured near the end of this arm H^2 is a 75 crank-pin, h^2 , projecting from that side of the crank-cam which is away from the valve-chest F . The projection or neck G^5 of the valve-chest forms a bearing, around which the crank-cam H' oscillates. The face h^3 of the crank-cam is provided with a notch or recess, H^3 , the depth of this recess being such that when the crank-cam is in position on the neck G^5 the end of said neck will reach to the bottom of the recess. After the crank-cam H' has been placed 80 in position on the neck G^5 , a sleeve, I , is placed on the valve-stem H , one end of said sleeve resting against the end of the neck G^5 and against the bottom of the recess H^3 in the crank-cam H' , thus holding the latter in position on the neck 85 G^5 , the sleeve being retained in position by a pin, I' , passed through said sleeve, and through the valve-stem H , and through the washer I^3 . The sleeve I is provided at that end which is 90 against the end of the neck G^5 with a lug or wing, I^2 , which rests in the recess H^3 in the crank-cam. The periphery of this wing is circular, and is coincident with the periphery of the hub h' of the crank-cam. The thickness of this wing I^2 is equal to the depth of the 95 recess H^3 , in which it rests; but its width is not quite so much as that of the recess H^3 , which construction permits a slight amount of rotation of the crank-cam in either direction before the sides of the recess will come in 100 contact with the sides of the wing I^2 . The purpose of this will be fully described when I treat of the operation of my invention.

The cylinder A^3 , before mentioned, is formed with a downward extension, J , the lower end of which is provided with a flange, J' , which latter is secured to the top of the box A^2 by appropriate bolts, thus securing the cylinder in position. In this extension J is formed a passage, J^2 , the upper end of which passage 110 communicates with the interior of the cylinder A^3 , opening into said cylinder at or near the bottom thereof, and the bottom of said passage J^2 communicates with a diagonal passage, j' , formed in the top of the box A^2 , and 115 communicating with the interior of the chamber a^2 of said box, as shown by dotted lines in Fig. 1. The extension J projects beyond the rear face of the cylinder A^3 , and is continuous with the ridge J^4 , formed on the side of the cylinder, and in this ridge J^4 and the projecting portion of the extension J is formed a passage, J^3 , the upper end of which communicates 120 with the interior of the cylinder A^3 at the extreme upper end of the cylinder, and the 125 lower end of said passage J^3 communicates with a diagonal passage, j , formed in the top of the box A^2 , and communicating with the interior of the chamber a' thereof, as shown 130

by dotted lines in Fig. 1. These passages J^2 and J^3 are illustrated by dotted lines in Figs. 1 and 2, and are shown in section in Fig. 4.

In the extension J is located a check-valve 5 or cock, K, which simultaneously controls the passage of fluid through both the passages J^2 and J^3 , enabling the amount of fluid and the force with which the fluid enters the cylinder A^3 to be regulated at will.

10 While I have described the passages J^2 and J^3 as being formed in the ridge J^4 and extension J, this being the preferred construction, it will be obvious that each of these passages may be in an independent pipe properly connected to the cylinder A^3 .

Within the cylinder A^3 is a piston, K' , which is connected to a piston-rod, K^2 , which latter passes up through the cylinder-head k , a suitable stuffing-box, k' , being provided.

20 At the sides of the cylinder A^3 are the pipes L L' , the pipe L communicating at its lower end with the passage J^3 , which latter passage enters the cylinder A^3 at its upper end, the upper end of said pipe L communicating with 25 the interior of the chamber A near the upper end of the latter, a check-valve, l , being present in said pipe to permit fluid to flow from said pipe into the chamber A, but prevent any return thereof. Above the check-valve l is a 30 screw, l' , or equivalent device, by the aid of which the valve may be set to regulate the amount of fluid to pass through the pipe L. The pipe L' communicates at its lower end with the passage J^2 , emptying into the bottom of 35 the cylinder A^3 , the upper end of said pipe L' communicating with the interior of the chamber A' near the upper end of the latter, a check-valve, l'' , and a screw or device, l''' , similar to the valve l and screw or device l , being 40 present in said pipe L' . The object of the pipes or conduits L L' is to enable cold liquid to be forced (when so desired) directly from the cylinder A^3 into the upper portion of 45 chamber A or A' , as the case may be, and thus condense the steam in the upper part of said chamber to form a vacuum to work the pump.

To the upper end of the piston-rod K^2 is connected a yoke, K^3 , having a longitudinal opening, K^4 , which yoke is placed on the 50 sleeve I on the valve-stem H, (see Fig. 5,) the sleeve passing through the opening K^4 in said yoke. Lugs or prongs k^2 k^3 project from one side of the yoke K^3 , said lugs projecting in the same direction as the arm H^2 of the crank-cam 55 H' , and projecting far enough to engage with the pin h^2 in the end of said arm as the yoke K^3 is raised and lowered. The yoke K^3 is retained in position on the sleeve I by a washer, I^3 , which washer is retained in position by 60 the pin I' , which latter passes through said washer, the sleeve I, and the valve-stem H. As the yoke K^3 is raised or lowered, one of the lugs k^2 or k^3 comes in contact with the pin h^2 in the arm H^2 of the crank-cam H' and 65 raises or lowers the end of this arm beyond the pivoted center of the cam, and any suitable spring is provided for moving the end of

this arm H^2 beyond the point to which it is moved by the lugs k^2 or k^3 . The preferred form of such spring is that shown in Fig. 1 of the 70 drawings, and is as follows: A bar-spring, M, is secured at one end to a lug, m , formed on the outside of the chamber A', the other end of said spring being pivoted to one end of a link, M' , the other end of said link being pivoted to the 75 end of the arm H^2 of the crank-cam, preferably by means of the pin h^2 . The tendency of this spring M is to constantly press toward the pivotal center of the crank-cam, for which reason, as soon as the connecting-point between 80 the link M' and the arm H^2 has passed the pivotal center of the crank-cam, either in an upward or downward direction, the pressure of the spring M moves the end of this arm beyond this point. The amount of movement 85 of the spring M, and consequently of the arm H^2 , is governed by a set-bolt, m' , which is screwed through a lug, m^2 , formed at some point on the outside of the chamber A', in such a position that the spring M, as it moves toward the chamber A', will strike against the 90 end of this bolt, preventing any further movement of the spring.

If desired, a block of rubber or wood may be connected to the end of the bolt m' , to deaden the sound of the spring M striking against the bolt. This bolt may be advanced or retracted to regulate the amount of movement of the spring, which regulates the amount of oscillation of the valve G.

A suitable escape-conduit, F^4 , communicates with the space G' of the valve, and through this escape passes the steam exhausted from either chamber. In this escape-pipe F^4 is located a check-valve, F^5 , which allows steam to 105 pass out from either of the chambers A A' as they are respectively put into communication with said escape-pipe, and prevent any return of fluid or air, &c., when a vacuum is created in either of said chambers.

In connection with that part of each chamber A and A' which communicates with the conduit to the valve-chamber is a screen, P, so located that the fluid or fluids passing through the said conduit to or from the cylinder must pass through the said screen. This screen consists, in general, of an outer box, p , provided with perforations p' , and containing any suitable porous cellular or granulated substance—as, for example, wire gauze, sand, shot, &c.—which will, when once heated by the steam passing for the first time, when the pump is started, through the conduit into the chamber, afterward heat the water or other liquid passing up from the chamber into said conduit to said valve-chamber, and thus prevent the live steam, when brought by the action of said valve into contact with said water in said conduit, from condensing; and for this reason the live steam acts at once upon the 125 surface of the water, and without agitating it, and hence operates the pump without loss of time or heat. That portion of the chamber A or A' or extension thereof which contains

said screen is made to be in close proximity to the exterior of said screen for the purpose of allowing only a thin edge or layer of liquid to be present around said screen. This thin layer of liquid is more readily heated by contact with the heated screen and the incoming live steam than a large quantity of liquid would be, and when the live steam enters the chamber it acts upon a hot layer of water distributed over the top surface of the liquid in the chamber, and hence, not being chilled by the cool liquid below said hot layer, it acts with force upon said liquid to drive it from said chamber. The preferable form of this space R between the screen and the chamber is as shown—viz., an annular space diminishing to a knife-edge; and this form of space is conveniently obtained by forming the interior of the cylinder in a cone shape, S.

I will now proceed to describe the mode in which my invention operates, and while my pump will operate to handle various liquids, for convenience of illustrating I will describe its operation when employed to pump water.

Suppose both chambers A and A' are filled with water and the piston K' of cylinder A³ to be at the lower portion of its stroke, the end H' of the crank-cam H' will be at the bottom of its stroke and the lug k² of the yoke K³ the length of the stroke below it. The valve G will be in a position such that the port g³ is uncovered, and the conduit f³ is put into communication with the live steam, and the conduit f² is put into communication with the steam-escape pipe F⁴. The live steam now first strikes against the thin edge or small surface of water at the entrance to conduit f³, and instantly heating it, without sensible condensation, forces this water down through the conduit and through the screen, at the same time heating the latter, and also heating that small quantity of water which is in advance of it and present in the screen. The live steam, pressing forward, occupies the screen, heats the thin layer of water in the space R at the sides of the screen, and, not being able to pass out of the impervious bottom of the screen, passing out of the sides of the screen, forces downward the heated layer of water in space R, and this layer of heated water, spreading over the entire surface of the cool water below it in the chamber, acts as a non-conducting wall between the steam above and the cold water below, and enables the live steam to act immediately, without condensation, and consequently effectually, upon the water beneath. The live steam forces the water out of chamber A', the water passing through orifice or conduit a³ into the receptacle a', and thence, lifting valve e', passes into chamber E, and thence through the discharge-pipe, communicating with the boiler or other receptacle which is to receive the water from this pump. A portion of the water at the same time passes from receptacle a' through pipe J' into the lower end of cylinder A³ and forces the piston therein upward. The piston, by

means of its piston-rod K², elevates the yoke K³, and the lug k² of said yoke acts upon and carries up the pin h², thereby moving the crank-cam H' and moving the valve, gradually closing the ports g³ g², and when the yoke has carried the crank-cam H' to the middle of the stroke of the latter the said cam and arm M' will assume the position shown in Fig. 1, the spring M now exerting most powerful pressure against arm M'. In bringing the cam H' and arm M' to this position the piston has had to overcome the resistance of the spring M to the straightening of the toggle-joint, the elbow of which joint, when the yoke was at the bottom of its stroke, pointed downward toward the chain-bars. The piston continues to move upward, and carries the end of the arm H² of the chambers H' a little above the horizontal plane passing through the axis of revolution of said cam, thus slightly breaking the toggle-joint upward, and instantly the pressure of the spring M, acting through one branch (viz., arm M') of the said toggle-joint, forces the elbow of the joint upward and brings the outer end of arm M' nearer to the center of the crank-cam H'. This sudden oscillation of the crank-cam carries up the valve to the full extent of its oscillation or stroke, and thus reverses the position it occupied when the piston K' was at the lower end of cylinder A³. The live steam is now shut off from conduit f³ and admitted to conduit f², leading to chamber A, and the conduit f³ now communicates with the escape-pipe f⁴. The live steam forces the water down the conduit f² and through the screen P and out of chamber A in a manner similar to what it did when previously admitted to conduit f³. The water, being forced out of chamber A through its lower orifice, a³, (see Fig. 4,) enters receptacle a', and thence, lifting valve e', passes into chamber E, and thence out the discharge-pipe C'. While the greater part of the water from chamber A is passing out the discharge-pipe C' a lesser portion of this water passes through orifice j, (see Fig. 1,) and thence through conduit J³ into the upper end of the cylinder A³ and above the piston k', and there acts upon said piston, forcing the latter down and carrying down with it the yoke K³. While the water is being forced down and out of chamber A the dead steam in chamber A' has in part passed out of the escape-pipe F⁴. As the piston k' begins to descend, as aforementioned, it forces the water below it out of the cylinder A³ in part back into chamber a', and forces another portion of said water through conduit L' and valve b² into chamber A', there condensing what dead steam has remained with said chamber A'. This condensation of steam causes a vacuum in chamber A', and check-valve F⁵ on escape-pipe F⁴ closes and prevents any air or fluid of any kind from entering the chamber A' through said escape-pipe. Where the outer or discharge end of the escape-pipe F is immersed in water or other liquid, this check-valve can be dispensed with. This vacuum in chamber

A' causes a flow of water through supply-pipe C into chamber B, thence through valve b^2 into chamber a^2 , and thence through orifice a^3 into chamber A', and fills the chamber A' full, and a portion of said water which passes up through screen P is then heated and goes up conduit f^3 to the valve. This chamber is now again ready to receive live steam from the steam-chest to empty said chamber, as first 5 and a portion of said water which passes up through screen P is then heated and goes up conduit f^3 to the valve. This chamber is now again ready to receive live steam from the steam-chest to empty said chamber, as first 10 aforescribed. The piston k' continues to descend, and as the yoke K³ comes down its lug k^3 comes in contact with the pin h^2 , and, overcoming the resistance of spring M, straightens the toggle-joint, and then breaks downward, whereupon the pressure of the spring M 15 instantly carries the crank-arm H² down and reverses the valve G in the steam-chest, and the live steam is now again admitted to chamber A', and empties it, as before mentioned. 20 While chamber A' is being emptied part of the dead steam in chamber A has escaped through escape-pipe F⁴ and the remainder has been condensed in the said chamber by the admission of water through pipe L, this last-named water being a part of the water which 25 was in cylinder A³ above the piston K', and which is forced out as piston K' rises while chamber A' is being emptied, and the remainder of the water in cylinder A³ above the said 30 piston is forced backward into chamber a' . Meanwhile chamber A is being filled by means of the vacuum formed within it, the water to fill it coming in through supply-pipe C into chamber B, thence through valve b' into chamber a' , and thence through orifice a^3 into said chamber A. This alternate action 35 of the pump in alternately filling and emptying the chambers is continued, and the water is continually taken up through supply-pipe C 40 and delivered through the discharge-pipe C'. In order to regulate the speed of the piston, and thus regulate the speed of the valve, and consequently of the pump, I provide a suitable device for controlling the amount of fluid 45 which shall pass through the conduits J² and J³. A preferred form of such device is shown in Figs. 1 and 2, and consists of the stop-cock K, provided with two openings to connect the 50 said conduits J² and J³. A preferred form of device for enabling the valve to remain in the position which it occupies at the beginning of the stroke of the piston-rod until the end of the crank-arm has been forced beyond the horizontal plane of the axis 55 of revolution of the crank-cam, and until the pressure of the spring or equivalent operating device is enabled to be exerted to carry the cam-arm the remainder of its stroke, and at the same time to limit the stroke of the crank- 60 cam, is shown in Figs. 1, 3, and 5. This device consists, as aforementioned, of the sleeve I, provided with lug or wing I², resting in the recess H³ in the crank-arm. As the recess 65 is wider than the wing I², and the wing is connected to and works the valve, the space between the edge of the recess and the edge of the wing must be traveled over as the arm H²

moves, before the arm H² can act to move the valve. The outer end of the crank-arm H² is therefore in advance of the valve, and as the 70 crank-arm H² travels it moves along, carrying with it the wing I², and when the end of crank-arm H² has passed the horizontal plane of revolution of the crank-cam and the toggle-joint is slightly broken and is in position for 75 the spring to take hold and break the joint still further, the valve has just closed both ports, and the pump would now stand on a dead-center and refuse to act; but as the toggle is now in a position for the spring to act 80 thereupon, the pump cannot remain inactive, as the spring necessarily acts to continue to break the toggle-joint, and in thus breaking the joint moves the valve and opens the ports. Other means besides the spring may be used 85 in connection with the toggle-joint and the recessed crank-arm H² and wing J² to complete the breaking of the toggle-joint—as, for example, an oscillating weight properly applied, or a steam-piston, and the like. 90

In the operation of the pump, as aforementioned, the pump is a direct-acting steam-suction and force pump. Where water is delivered into the inlet-pipe C under pressure, that feature of my invention which causes a 95 suction in the chambers may be omitted, and then the pump becomes a direct-acting force-pump. For example, by shutting the valves l^2 in the conduits L and L', no liquid can pass 100 into the chambers from said conduits to condense the steam in said chambers, and the dead steam in the chamber will be forced out by the water flowing in through the bottom orifice, a^3 , the chamber being filled by the pressure of water through the inlet-pipe C. 105

In the mechanism as herein described the lugs k^2 k^3 of the yoke K³, in fact, strike against the boss of the arm M', which boss encircles the pin h^2 . For convenience of description, the lugs k^2 k^3 of the yoke K³ have been described as striking directly against the pin h^2 . When the arm M' is connected, as will be often the case, to a different portion of the pin h^2 from that hence shown, or to a separate arm, and the spring located in another position, the 115 said lugs k^2 k^3 will directly impinge against said pin h^2 .

In place of a spring, as M', or equivalent of other form, there may be employed a bob-weight or steam-pressure. When preferred, the cylinder A³ may move and its piston be stationary; also, the position of said cylinder and piston relatively to the other parts of the pump may be altered, obvious corresponding changes being made in the connecting mechanism. 125

While liquid is preferred for operating the cylinder A³ and its piston, steam, or air, or other fluid may be employed for operating the same. 130

The various features of my invention are preferably employed together; but one or more of said features may be employed apart from the remainder, and one or more of the

said features may be employed, so far as applicable in connection with purposes other than that specifically herein described.

What I claim as new and of my invention, 5 and desire to secure by Letters Patent, is—

1. In a direct-acting steam force-pump, the combination of the two chambers A and A' and a valve for alternately supplying said chambers with steam, and means for compelling 10 a portion of the fluid as alternately discharged from the chambers to operate the valve, and means for controlling the flow and amount of such fluid operating the valve, substantially as and for the purposes specified.
- 15 2. In a direct-acting steam force and vacuum pump, the combination of the two chambers A A', and a valve for alternately supplying said chambers with steam, and means for compelling a portion of the liquid as alternately discharged from the chambers to operate the valve, and afterward to condense the steam which previously discharged it (said liquid) from said chamber, substantially as and for the purposes specified.
- 25 3. In a direct-acting steam force and vacuum pump, the combination of the two chambers A A' and a valve for alternately supplying said chambers with steam, and means for compelling a portion of the liquid as alternately 30 discharged from the chambers to operate the valve, and afterward to condense the steam which previously discharged it from said chambers, and the check-valve in the exhaust-pipe, substantially as for the purposes specified.
- 35 4. In a direct-acting steam force and vacuum pump, the combination of the chambers A A' and a valve for alternately supplying said chambers with steam, and the double-acting cylinder A³, provided with piston and conduits L L' and valves l l', and suitable mechanism for enabling the fluid in the cylinder A³ to operate said valve, substantially as and for the purposes specified.
- 45 5. In a direct-acting steam force and vacuum pump, the combination of chambers, as A A', and a valve for intermittently supplying said chambers with steam, and the double-acting cylinder A³, provided with piston and 50 conduits, substantially as specified, for enabling the fluid in the cylinder and on one side of the piston to force the fluid which is on the other side of the piston, and which was received from the chamber A or A', back into the 55 chamber from which it was received, but through another passage connecting with said chamber at its upper part, for condensing the steam in said chamber after said steam has done its work, and mechanism for enabling the fluid in the cylinder to operate said valve and check-valve in the exhaust, substantially as and for the purposes specified.
- 60 6. In a direct-acting steam force and vacuum pump, the combination of the chambers A A' and a valve for alternately supplying said chambers with steam, and the double-acting cylinder A³, provided with piston and con-

duits, substantially as specified, for enabling the fluid in the cylinder which is on one side of the piston to force the fluid which is on the other side of the piston into the same chamber from which it was originally received, but through another passage connecting with the upper part of said chamber, for condensing the steam in said chamber after said steam has done its work, and mechanism for enabling the fluid in the cylinder to operate said valve, substantially as and for the purposes specified.

7. In a direct-acting steam force and vacuum pump, the combination of a main chamber 80 and a valve for intermittently supplying said chamber with steam, and the double-acting cylinder A³, provided with piston and conduits, substantially as specified, for enabling the fluid in the cylinder and on one side of the piston to force the fluid which is on the other side of the piston, and which was received from the chamber, back into the said chamber, but through another passage connecting with said chamber at its upper part, for intermittently condensing the steam in said chamber, and the device 85 for controlling the passage of fluid to and from the said cylinder, and mechanism for enabling the fluid in the cylinder to operate said valve, substantially as and for the purposes specified.

8. In combination, the chambers A A', provided with induction and eduction valves, and the double-acting cylinder A³, and mechanism for enabling the fluid in the cylinder to alternately supply the chambers A A' with steam, substantially as and for the purposes specified.

9. In combination, the chambers A A', provided with induction and eduction valves, and the double-acting cylinder A³, and device 105 for controlling the passage of fluid to and from said cylinder, and mechanism for enabling the fluid in the cylinder to alternately supply the chambers A A' with steam, substantially as and for the purposes specified.

10. In combination, the chambers A A' and the cylinder A³, and a valve for alternately supplying said chambers A A' with steam, and conduits J² J³, orifices j j', chambers a' a², valves b' b², chamber B, inlet-pipe C, orifices 115 a³, valves e' e², chamber E, and discharge-pipe C', and mechanism for enabling the fluid in cylinder A³ to operate said valve, substantially as and for the purposes specified.

11. In combination, the chambers A A' and the cylinder A³ and a valve for alternately supplying said chambers A A' with steam, and conduits J² J³, conduits L L', valves l l', orifices j j', chambers a' a², valves b' b², chamber B, inlet-pipe C, orifices a³, valves e' e², chamber E, and discharge-pipe C', and mechanism for enabling the fluid in cylinder A³ to operate said valve, substantially as and for the purposes specified.

12. In combination, the chambers A A' and the cylinder A³ and a valve for alternately supplying said chambers A A' with steam, and conduits J² J³, stop-cock K, conduits L L', valves l l', orifices j j', chambers a' a², valves

b' b², chamber B, inlet-pipe C, orifices *a³*, valves *e' e²*, chamber E, and discharge-pipe C, and mechanism for enabling the fluid in cylinder A³ to operate said valve, substantially as and for the purposes specified.

13. In a direct-acting steam force-pump, a valve for alternately supplying chambers with steam for the expulsion of a liquid therefrom, and means for compelling a portion of the fluid discharged from the chamber to begin to operate the valve when the device for operating the valve, and which is operated by the fluid from the chamber, has nearly completed its movement, and shall then (by the remainder of its movement) cause the valve to be instantly operated, substantially as and for the purposes specified.

14. In a direct-acting steam force-pump, the combination of a valve for alternately supplying chambers with steam for the expulsion of a liquid therefrom, and a wing, I², and crank-cam H', provided with recess H³, and means for enabling said crank-cam to be operated by the positive pressure of a portion of the liquid discharged from said chamber, and for operating said valve, substantially as and for the purposes specified.

15. In combination, the valve G, wing I², crank-cam H', yoke K³, provided with lugs k², k³, pin h², arm M', and spring M, substantially as and for the purposes specified.

16. In a direct-acting steam force-pump, a valve for supplying a chamber with steam for expelling liquid therefrom, and the screen P, consisting of a cylinder perforated at its sides and impervious at its end p, and containing porous cellular or granulated substances, and forming the only channel of communication between the said chamber and the valve-port, substantially as and for the purposes specified.

17. In a direct-acting steam force-pump wherein the liquid in the main pump-chamber is expelled by the direct action of the steam upon the surface of said liquid, a perforated screen located in the apex of a conically-formed

portion of the said pump-chamber, and forming the only channel of communication between the chamber and the port, the space between the exterior of the screen and the interior surface of the chamber gradually diminishing upward to a thin edge, substantially as and for the purposes specified. 50

18. In combination, the valve having wings g², ports g³, conduits f² f³, screens P, and conically-formed chambers A A', and exhaust-port F⁴, substantially as and for the purposes specified. 55

19. The combination of an oscillating valve and ports g³, conduits f² f³, conically-formed chambers, screens located in the apex of said chambers, and exhaust-port F⁴, substantially as and for the purposes specified. 60

20. The combination of a valve and port g³, conduit f², a screen, a main pump-chamber, and exhaust-port F⁴, substantially as and for 65 the purposes specified.

21. The combination of a valve and ports g³, conduits f² f³, conically-formed chambers, screens located in the apex of said chambers, and exhaust-port F⁴, having check-valve F⁵, 70 substantially as and for the purposes specified.

22. In combination, the pipes L L', valves l l', main pump-chambers, and exhaust provided with check-valve F⁵, substantially as and for the purposes specified. 75

23. The combination of the chambers A A', suitable eduction and induction valves, oscillating steam-valve ports g³ g³, conduits f² f³, and screens, substantially as and for the purposes specified. 80

24. The pump-chambers, with suitable induction and eduction valves, piston-cylinder, with proper mechanism to operate steam-valve, in combination with a valve or cock to regulate the flow of fluid into the cylinder, substantially as and for the purposes specified. 85
